ATOMIZER

Joy B. Schmitt and Alvin J. Attinger, Toledo, Ohio, assignors to The De Vilbiss Company, Toledo, Ohio, a corporation of Ohio

Application May 11, 1945, Serial No. 593,230

5 Claims. (Cl. 299—88)

This invention relates to atomizers of the type used for applying medicine and perfume preparations.

The principal object of the invention is to provide an atomizer that is sufficiently compact for carrying in a purse or pocket.

Another important object is an atomizer that is inexpensive to produce with a minimum number of parts.

Another object of the invention is the provision of an atomizer with effective closure means to prevent leakage while the atomizer is not in use.

Other objects and advantages of the invention will be apparent upon reading the following description with reference to the accompanying drawing in which:

Figure 1 is a side elevation partly in vertical section of an atomizer embodying our invention;

Figure 2 is a horizontal section taken on line 2—2 of Figure 1; and

Figure 3 is a fragmentary vertical section of the nozzle portion of a modified form of the invention.

The atomizer has a main body 1, formed of two cylindrical sections at right angles to each other, one section having a vertical bore 2 constituting a liquid reservoir, and the other section having a laterally facing shallow, approximately cylindrical cavity 3 forming, with a rubber diaphragm 4, an air compression chamber. The liquid reservoir 2 has a filling opening at its bottom which is closed by cap 5 and gasket 6. At the other end of the bore is inserted nozzle plug 7 which may be press-fitted into position. Supported by this plug is a liquid outlet tube 8 which passes through the plug and terminates with discharge tip 9. In the nozzle shown in Figure 1 the plug 7 has an annular air receiving chamber 10 to which air is delivered from air supply chamber 3 through passage 11.

From the annular chamber 10, air is forced with each compression of diaphragm 4 through port 12. With the closure cap 13 and its accompanying gasket 14 removed, air from port 12 passes over the end of liquid nozzle 9 drawing liquid therefrom and atomizing it along a path substantially coaxial with passage 12.

In order to prevent a vacuum being created within liquid chamber 2 by the continued discharge of atomized liquid, a small port 15 is provided in the upper end of tube 8. Between compressions of the diaphragm 4 air enters the nozzle 9 and passes into chamber 2 through port 15 to take the place of any liquid that has previously been discharged.

The modification shown in Figure 3 has a nozzle plug 1a exteriorly shaped for spraying into nasal passages. Instead of a cross jet atomization arrangement, this nozzle uses a form in which atomizing air is discharged from an annular opening surrounding the liquid tip. This type may give more satisfactory results when used with medicinal preparations.

Instead of having the annular chamber 10 of nozzle plug 7 in Figure 1, nozzle plug 1a of Figure 3 has a cut-away section 16 extending only a short way around the plug. Air is delivered to it from passage 11 and reaches the nozzle through continuing passage 17, and the annular space 18 around the tip 9a.

While this modification has more nozzle parts, its construction is otherwise similar and as uncomplicated in design as that of Figure 1.

It may be seen that the invention provides an atomizer the slim shape of which is particularly well-suited for insertion into a pocket or purse. The long narrow liquid reservoir and the shallow air chamber fit together neatly within the contours of the atomizer body and cooperate in making possible such a desirable shape. Also the design enables the air and liquid chambers to be formed in the molding operation. This and the insertable nozzle plug reduce machining operations to a minimum.

We wish it understood that our invention has been disclosed herein by way of example only and that numerous modifications therein may be devised without departing from the inventive concept.

Having thus described our invention, what we claim to be new and desire to secure by U. S. Letters Patent, is:

1. In an atomizer, a single integral body member having a vertical bore at one end, a laterally facing shallow cavity near the other end, a rubber diaphragm attached over the cavity to form an air compression chamber, an air passage between the cavity and the vertical bore, a nozzle plug fitted into the bore, an indentation on one side of the plug with which the air passage from the cavity communicates, a liquid outlet tube having a discharge nozzle and depending from the plug and an air passage from the indentation for directing an atomizing jet of air around the end of the liquid discharge nozzle.

2. In an atomizer, an integral vertically flattened body formed of two merging cylindrical sections the axis of each section disposed in a plane perpendicular to and bisecting the axis of the other section, the axis of each section being

substantially equal in length to the diameter of the other section, a chamber in each section coaxial therewith, one for atomizing air and the other for liquid to be sprayed, a spray nozzle near one end of the liquid chamber, passages from the liquid and air chambers to the nozzle, and compressible means associated with the air chamber for impelling air therefrom to the spray nozzle.

3. In an atomizer, an integral body formed by two cylindrical sections with the axis of each in a plane perpendicular to and bisecting the axis of the other, the center points of the axes being spaced apart approximately the sum of the radii of the two sections, substantially planar surfaces joining the sections together, a cavity in and coaxial with each section constituting respectively a liquid reservoir and an air chamber, a spray discharge nozzle mounted on the body, passages from the liquid reservoir and the air chamber to the spray nozzle and compressible means associated with the air chamber for forcing air from the chamber to the spray nozzle.

4. In an atomizer, an integral body member

flattened vertically, a vertical bore near one end for holding liquid, an atomizing nozzle at the upper end of the bore, a filling cap covering the other end of the bore, a shallow cavity facing laterally from a flattened vertical side of the body, a rubber diaphragm attached over the cavity and forming therewith an air compression chamber, and a passage from the cavity to the upper end of the bore to deliver atomizing air to the nozzle when the rubber diaphragm is depressed into the cavity.

5. In an atomizer, a cylindrical bore forming a liquid reservoir, an atomizing plug inserted in the end of the bore, said plug having a flaring conical opening in the center of its exterior end, a liquid outlet tip extending outwardly from the apex of the conical opening, an air port in the wall of the conical opening positioned to direct air across the end of the liquid outlet tip, and manually compressible means for delivering air through said port.
